PHONOGRAPH RECORD CHANGING
APPARATUS

Paul F. Wilber, Richland, N. Y.

Application December 14, 1936, Serial No. 115,666

19 Claims. (CL. 274—10)

This invention relates to improvements in a phonograph record changing apparatus in which means is provided for removing a disc record from a magazine and placing it on a turntable and for removing the record from the turntable and returning the same to the magazine.

One of the main objects of the invention is to provide a phonograph with an automatic record changing apparatus whereby any one of a group of records may be selected and placed on a turntable for playing.

Another object of the invention is to provide an apparatus of the above mentioned class which, during the shifting of the records to bring them into and out of operative relation with the turntable, will reverse the position of the records whereby the records may be played either on one side or on both sides without manually removing the records from or rearranging the same in the record changing apparatus.

A further object of the invention is to provide a record changing apparatus for phonographs with a magazine for maintaining a plurality of records, whether of ten inch or twelve inch size or of some other diameter or some of each, in predetermined order and a record selector and carrier mechanism which is adapted to remove any desired record from the magazine and place the same on the turntable irrespective of the size of the record or the arrangement thereof in the magazine relative to the remaining records.

A still further object of the invention is to provide a phonograph with an apparatus for automatically moving disc records from a magazine and placing them onto a turntable for playing and then returning the played record to the magazine which is simple, economical and durable in construction, and that is positive and dependable in operation.

A more specific object is to provide a record changing apparatus with a magazine having a plurality of separate compartments, one for each record whereby the records will be maintained in spaced relation to each other and thereby prevented from becoming scratched or damaged.

Another specific object is to provide an improved mechanism for positioning a record upon a turntable of a phonograph in concentric relation therewith and wherein its efficiency will not be impaired either by variations in the diameters of the records or by wear between relatively movable parts thereof incident to long use.

A further object of the invention is to provide a record changing apparatus which may be operated by a minimum amount of power, said latter

object being accomplished by providing a stationary magazine for the records and a relatively light, easily operated movable record selector and carrier mechanism for successively transferring the records contained in the magazine to and from the turntable of the phonograph.

A still further object of the invention resides in providing a record changing apparatus for phonographs which is adapted to be operated either by the motor for rotating the phonograph turntable or by other power means separate therefrom.

Yet another object is to provide a record changing apparatus which may be manually adjusted to effect the playing of any desired record or records contained in the magazine a second time either on one side or on both sides without changing the location thereof in the magazine.

Other objects and advantages relating to the structure of the apparatus and to the form, relation and operation of the parts thereof, will more fully appear from the following description taken in connection with the accompanying drawings, in which:

Figure 1 is a detail vertical sectional view of the upper portion of a phonograph case having a turntable mounted therein and with my novel record shifting apparatus operatively connected therewith.

Figure 2 is a detail vertical sectional view taken on line 2—2, Figure 1, illustrating the manner of transmitting motion from the drive shaft to a cam shaft.

Figure 3 is a detail horizontal sectional view taken on line 3—3, Figure 1, illustrating the manner of controlling the clutch for operatively connecting the drive shaft with the cam shaft or with the turntable shaft.

Figure 4 is an enlarged detail vertical sectional view taken on line 4—4, Figure 15, illustrating a manually operated control means associated with the record selector and carrier mechanism whereby the playing of any one record or number of records contained in a magazine may be caused to be played on both sides.

Figure 5 is a detail horizontal sectional view taken on line 5—5, Figure 4.

Figure 6 is a detail vertical sectional view taken substantially in the plane of the line 6—6, Figure 1, illustrating the manner of operating the record carrier arms.

Figure 7 is a detail vertical sectional view taken on line 7—7, Figure 1, illustrating the manner of operating a movable track member connected

with the record selector mechanism and the record positioning fingers associated therewith.

Figure 8 is a detail vertical sectional view taken on line 8—8, Figure 1, illustrating the manner of reversing the records.

Figure 9 is a detail horizontal sectional view, partly broken away, taken in the plane of the line 9—9, Figure 6, illustrating the relation of a portion of the record selector and carrier mechanism with the turntable and the tone arm associated therewith.

Figure 10 is an enlarged detail vertical sectional view taken substantially in the plane of the line 10—10, Figure 1, illustrating a portion of the carriage associated with the record selector and carrier mechanism and means for intermittently operating the same.

Figure 11 is a fragmentary side elevation of a portion of the carriage operating mechanism illustrated in Figure 10 showing the same in two successive positions for adjusting the carriage and locking the same in the adjusted position.

Figure 12 is a detail horizontal sectional view taken on line 12—12, Figure 10.

Figure 13 is a detail horizontal sectional view taken on line 13—13, Figure 6.

Figure 14 is a detail transverse sectional view taken on line 14—14, Figure 15.

Figure 15 is a detail horizontal sectional view taken substantially in the plane of the line 15—15, Figure 1, illustrating the carriage and the adjacent portion of the record selector and carrier mechanism in plan view and with portions of the magazine and support for the carriage broken away and in section.

Figure 16 is an enlarged detail vertical sectional view taken substantially on the line 16—16, Figure 14.

Figure 17 is a diagrammatic view illustrating various power operated members of my novel record shifting device together with electrical control means and circuits associated therewith.

In order that the invention may be clearly understood, I have shown a portion of a phonograph cabinet or case A having side walls a and a shelf or partition a' disposed in a horizontal plane intermediate the side walls a for supporting a motor B and a turntable C. The cabinet is also shown provided with a second wall or shelf a'' arranged above the partition a' for supporting a tone arm D in cooperative relation with the turntable C.

The motor B is preferably of the electric type and may be of any suitable construction. This motor as shown in Figure 1 is secured to the lower side of the shelf a' and has the armature shaft b thereof journaled at its outer end in a suitable bracket 1 also secured to the shelf a''. The turntable C has the shaft c thereof journaled in a suitable bearing support 2 secured to the upper portion of the shelf a' and which is connected with the motor shaft b by a bevel gear 3 secured to the turntable shaft and a similar bevel gear 3' mounted on the motor shaft b.

The tone arm D having the reproducer d carried thereby, may be connected in any suitable manner with the usual amplifier, not shown, and may be operated in any suitable manner relative to the amplifier and supporting shelf a'' to swing in the usual manner across the surface of a record E on the turntable C for reproducing sound from the record in the usual manner.

* My novel record shifting apparatus as illus-

trated in the drawings comprises primarily a record magazine 4 secured to the cabinet A above the turntable C and preferably at the rear thereof, a record selector and carrier mechanism 5 mounted in cooperative relation with the magazine and with the turntable C for movement relative to both of these members and a power operated means 6 actuated by the motor B for operating the selector and carrier mechanism.

The record magazine 4 as shown comprises a plurality of, in this instance, thirteen upright frames 8 composed of wire. These frames are secured to a pair of side rails 9 arranged one at either side of the wire frames and fixedly secured to a respective side wall a of the cabinet by brackets 10 as shown in Figures 1 and 15. The frames 8 are arranged in parallel relation with each other longitudinally of the rails 9 and are spaced apart a distance to readily receive a phonograph disc record therebetween.

The side rails 9 extend in parallel relation to each other from a position over the turntable rearwardly to a position at the rear of the magazine frames 8 for supporting the record selector and carrier mechanism 5 in cooperative relation with the frames 8. These side rails 9 are preferably in the form of channel members with the channeled sides thereof facing inwardly toward each other to form a track for supportably receiving wheels 11 rotatably connected to opposite sides of a carriage 12 mounted beneath the magazine frames 8 for movement longitudinally of the rails relative to said frames. This carriage 12 comprises two side members 13 to which the wheels 11 are secured and a horizontally disposed platform 14 which connects the side members and extends in a horizontal plane beneath the magazine frames 8 in close proximity thereto.

This platform 14 is provided with an opening 15 which extends longitudinally thereof substantially midway between the sides of the carriage. The platform 14 is also provided with a pair of slots 16, see Figure 15, arranged one on either side of the opening 15. These slots 16 extend outwardly from the corresponding side of opening 15 intermediate the ends thereof and in aligned relation with each other toward the respective longitudinal sides of the platform. These slots 16 are of slightly greater width and over all length than that of the largest record to be mounted in the magazine to receive the record therethrough. The slots 16 and the frames 8 are preferably arranged at a slight inclination to the vertical as indicated in Figures 6, 8, 10 and 16 so that when the record is supported by the frames the same will be maintained slightly inclined from the perpendicular toward the turntable. Each side wall of the slots 16 adjacent the opening 15 has the upper edge thereof beveled as at 16' to permit a record when being returned to the magazine to readily move into contact with the upper surface of the platform 14 adjacent the opening 15 in a manner which will hereinafter be more apparent.

Secured to the carriage 12 to move therewith is a record guide means 18 which in this instance comprises a stationary track 19 and a movable track 20. The stationary track 19 is substantially a U-shaped member having the transverse portion thereof arranged uppermost and connected by means of rearwardly extending arms 21 and a pendant support 22 to the rear end of the carriage 12 so that the arms as 23 extend

5 downwardly in alignment with the rear side walls of the slots 16. The greater portion of arms 23 extend downwardly from the transverse portion of the guide track in slightly diverging planes in substantially the same angle of inclination as the frame member 8. The lower ends of the arms 23 terminate in a horizontal plane a relatively short distance above the turntable C and are slightly curved forwardly for assisting in 10 guiding the record to a horizontal position over the turntable.

10 The movable guide track 20 is also a substantially U-shaped member having the side arms 24 thereof spaced apart a distance greater than the diameter of the turntable C and less than the diameter of the smallest record to be played as 15 illustrated in Figure 9. The free ends of the arms 24 are pivotally secured as at 25, Figures 6, 8, 9 and 14 to the carriage 12 one at either side 20 of the stationary track 23 and opening 15 and with the forward edge thereof in alignment with the rear edges of the slots 16. The arms 24 extend downwardly in substantially straight lines from the pivots 25 and then are curved forwardly 25 so that when the upper portions thereof lie in a plane substantially parallel with the forward edges of the upper portion of the arms 23 the lower or forward portions 24' thereof will extend in substantially a horizontal plane above the 30 turntable C as shown in Figure 6 and with the transverse portion 26 of the track positioned forwardly of the turntable as shown in Figure 9.

35 It will now be seen that the movable track 20 may swing about the pivots 25 from a position with the lower portion 24' of the arms 24 located in a horizontal plane above the turntable as shown in Figure 6 when the rear or upper portion of the arms are in the transverse plane of the upper portions of the arms 23 to a position 40 below said turntable as shown in Figure 7.

45 The means for operating the movable guide track 20 to bring the forward portions 24' of the side arms thereof from the position above the turntable C to a position below said turntable and return, comprises a pair of cams 28 mounted on a horizontally disposed cam shaft 29 which extends transversely through the cabinet A in a plane below the turntable C and at one side of the turntable shaft c. This shaft 29 as shown in 50 Figure 1 has the ends thereof journaled in suitable bearing supports 30 secured to a corresponding side wall a of the cabinet and which is rotated by the motor B in the manner herein-after described.

55 The carriage 12 is intermittently moved relative to the magazine frames 8 to bring the slots 16 and the guide tracks 19 and 20 into cooperative alignment with the chambers 8' between said frames as shown in Figures 6, 10 and 11 by the 60 mechanism which will now be described. Secured to or made integral with the carriage 12 is a rack 32 which is positioned along one longitudinal side of the carriage beneath the platform 14 as shown in Figures 1 and 10. This rack 32 is 65 provided with at least as many teeth as there are record chambers 8' in the magazine 4 and they are spaced apart a distance substantially equal to the distance between adjacent chambers. Mounted beneath the rack 32 is an operating pawl or 70 detent 33 which is connected by a pin 34 to a supporting block or bracket 35 secured to the adjacent side wall a of the cabinet A. This pin 34 extends through an elongated slot 34' formed in the detent 33 intermediate the ends thereof.

75 A spring 36 connected with the forward end of

the detent and with the support 35 yieldingly urges said end of the detent downwardly out of engagement with the rack 32 while a stop pin 37 secured to the support 35 extends over the rear end portion of the detent and limits the swinging movement of said detent produced by the spring 36. The rear end of the detent 33 is pivotally connected as at 38 with one arm of a bell-crank lever 39 which is secured by means of a pin 40 with the support 35. The pin 40 extends 10 through an elongated slot 40' as shown in Figure 10 arranged below the pivot 38. The other arm as 39' of said bell-crank lever is connected with a spring 41 secured to the support 35 and which normally urges the outer end of the arm 39' upwardly. This upward movement of the arm 39' is 15 limited by a stop pin 42 secured to the support 35.

20 The bell-crank lever 39 is operatively connected with a cam follower 44 by means of a link 45 pivotally connected at one end as at 46 to the 25 arm 39' of the bell-crank lever intermediate the ends thereof. The other end of the link 45 is pivotally connected as at 47 with the cam follower 44 which in turn is pivotally secured as at 48 to a supporting bracket 49 mounted upon 30 the shelf a' at the rear of the cam shaft 29 as shown in Figure 6. The cam follower 44 in this instance is an L-shaped member with one leg 44' thereof extending upwardly from the pivot 48 through a slot 50 provided in a guide member 51 35 connected with the bracket 49. The cam follower 44 is maintained in operative engagement with a cam 53 by means of the spring 41 acting upon the lever 39'.

35 The cam 53 is secured to a vertically disposed shaft 54 which is journaled in the bracket 49. The shaft 54 extends upwardly some distance above the cam 53 and has the upper end thereof secured to a bevel gear 55 which is in meshing engagement with a bevel gear 56 secured to a 40 horizontally disposed stub shaft 57 which is journaled in a bracket 58 secured to the shelf or partition a'. The shaft 57 is driven by the cam shaft 29 at one-half the speed of said cam shaft by means of a shaft 60 journaled in a bracket 61 45 secured to the partition a'. One end of the shaft 60 is connected with the shaft 57 by a relatively large bevel gear 62 secured to the latter shaft and a pinion 63 secured to the shaft 60. The other end of shaft 60 is connected with cam shaft 29 50 by a pair of bevel gears 64 as shown in Figure 13.

55 The cam 53 is of disc formation having a smooth peripheral edge with the exception of a slight cam indentation or recess 53' formed therein adapted to receive the adjacent portion of the cam follower 44 therein to effect rocking of said follower about its pivot 48. The cam 53 is provided with a switch actuating pin 66 which is secured thereto diametrically opposite the recess 53'. This pin 66 projects below the adjacent portion of the cam 53 for engagement with one of the contact members 67 of a control switch 68 when the cam follower 44 is in engagement with the slot 53' for opening said switch. Associated with the cam 53 is a second switch 69 arranged about the shaft 54 in right-angular relation with the switch 68. This switch 69 has one of the contact arms as 70 thereof projecting into the path of movement of the pin 66 to be moved thereby out of electrical connection with the other contact member as 70' of the switch. These switches 68 and 69 are actuated by the pin 66 on the cam 53 for controlling the drive connection between the motor shaft b and the cam 75

shaft 29 in a manner and for a purpose which will hereinafter be described.

The means as shown in Figures 1 and 2 for operatively connecting the cam shaft 29 with the motor shaft b comprises a relatively large spur gear 72 secured to the cam shaft to rotate therewith, an idle gear 73 rotatably mounted upon a shaft 74 secured to the bracket 1 and a similar bracket 1' mounted on the wall or shelf 10 a' and a relatively small spur gear 75 mounted on the shaft b.

It will be observed by referring to Figures 1 and 3 that the gear 75 is arranged in spaced relation longitudinally of the shaft b to the gear member 3'. Furthermore, both of these gear members 75 and 3' are rotatably mounted upon the shaft b and have their adjacent surfaces provided with clutch elements 76 and 77 respectively, which are adapted to be engaged by a clutch member 78 slidably mounted upon the shaft b intermediate the gear members 76 and 3'. This clutch member 78 is keyed to the shaft b as indicated in Figure 3 so as to rotate with said shaft and is moved longitudinally of said shaft to bring the same into and out of forked engagement with the clutch members 76 and 77 by means of a forked arm 79. This arm 79 is pivotally connected intermediate its end as at 80 to a bracket 81, Figure 1, secured to the lower surface of the shelf or wall a'. The rear end portion of the arm 79 is composed of magnetizable metal and is mounted between a pair of electro-magnets 82 and 83 which may be secured in any suitable manner to the wall a' in cooperative relation with the arm 79 for actuating said arm when energized.

It is thus seen that when the clutch member 78 is in engagement with the clutch element 76, the cam shaft 29 will be rotated by the motor shaft b through the medium of the gears 75, 73 and 72 while the turntable C may remain stationary. When the clutch 78 is moved into clutching engagement with the clutch element 77 the motor shaft b will be connected from the gear 75 and cam shaft 29 and will be operatively connected with the gear 3' and turntable shaft c. It will now be observed that while the turntable C is operated at a relatively high rate of speed by the motor B, the cam shaft 29 is operated at a much slower rate of speed depending upon the relative sizes of the gear member 75 and 72. Furthermore, it will be observed that the cam 53 for intermittently actuating the carriage 12 is rotated at one-half the speed of the cam shaft 29 so that the detent 33 is actuated to move the carriage one tooth space due to the engagement of the cam follower 44 with the cam recess 53' but once during two revolutions of the cam shaft. The manner in which the cam 53 effects the intermittent movement of the carriage will be readily understood by referring to Figures 10 and 11.

It will be observed by referring to Figure 10 that when the cam follower 44 is in registration with the cam recess 53' the spring 36 will maintain the forward end of the detent 33 in its lowermost position as determined by stop pin 37. At the same time the detent will be urged forwardly so as to maintain the pivotal pin 34 in engagement with the rear end of the slot 35. This action of the spring 36 upon the detent 33 also maintains the vertical leg of the bell-crank 39 in its uppermost position with the pivotal pin 40 positioned at the lower end of the slot 40'. The spring 31 is of sufficient tension to maintain

the arm 39 in engagement with the stop pin 42 when the cam follower is in registration with the cam recess 53' and thereby urge the free end of the cam follower toward the cam into engagement therewith. As the cam 53 is rotated in the direction of the arrow X in Figure 12, the cam follower is rocked about its pivot 48 as the recess 53 is moved beyond the said follower. During the initial rocking movement of the cam follower 44 thus produced the vertical leg of the bell-crank 39 is drawn downwardly until the pin 40 is in engagement with the upper end of the recess 40' as shown by full lines in Figure 11 due to the spring 41 being stronger than the spring 36. This downward movement of the bell-crank lever 39 effects the forward swinging movement of the forward end of the detent 33 and brings the same into operative engagement with the tooth in the rack 32 aligned therewith. As the cam follower continues to be rocked about its pivot 48 as the same moves from the cam recess 35' into contact with the peripheral surface of the cam, the bell-crank lever 39 will be rocked about the pin 40 as a pivot against the action of the spring 41, that is, to the position indicated by broken lines in Figure 11. This rocking of the bell-crank lever 39 draws the detent 33 rearwardly a sufficient distance to move the rack 32 and therefore the carriage 12 rearwardly one tooth space.

It will now be observed that inasmuch as the cam follower 44 is maintained in the rocked position until the cam 53 has made substantially one complete revolution, the detent 33 will be maintained in holding engagement with the rack 32 and will thereby lock the carriage 12 against being moved relative to the magazine 4 until the detent 33 is again moved out of engagement with the rack 32 as the cam follower 44 again moves into the cam recess 53'. As said follower engages said recess the detent 33 will be moved out of engagement with the rack 32 and returned to its initial inoperative position by the action of the spring 36 with the forward end of the detent in operative alignment with the next succeeding tooth in the rack 32.

It will be obvious that, when the cam follower 44 is in engagement with the cam recess 53' and the detent 33 is in the inoperative position, the carriage 12 is free to be moved along the rails 9 relative to the magazine 4. In order that this may be readily accomplished manually I have shown the carriage provided with a lever 85 which is shown in Figure 15 secured to the forward edge portion of the platform 14 and extends laterally therefrom over the adjacent side rail 9 and through an elongated slot 86 provided in the adjacent side wall a' of the cabinet A to the exterior of said cabinet. It will now be apparent that as the carriage 12 is moved longitudinally of the supporting rails 9 whether manually through the medium of the lever 85 or by power means through the medium of the detent 33 and rack 32, the slots 16 will be brought into successive alignment with the chambers 8' of the magazine 4. As the slots 16 thus register with each chamber 8', the record E contained in said chamber will be in position to pass downwardly through the slots 16 and onto the guide tracks 19 and 20, while the remaining records will be maintained in the chambers by the engagement of said records with the portions of the platform 14 extending along the sides of the opening 15.

In order to control the movement of the rec-

ords through the slots 16 I have provided a pair of record carrier arms 88 which are secured at their forward ends to a shaft 89 journaled in the forward ends of the side rails 9 as illustrated 5 in Figures 1, 6 and 15 so as to rotate with said shaft. These arms extend rearwardly from the shaft 89 in parallel spaced relation with each other and with each arm positioned within the opening 15 in close proximity with a respective 10 side of said opening. The upper surface of the arms 88 when the arms are in their normal position within the opening 15, are arranged in a horizontal plane a slight distance above the lower corner of the beveled or chamfered portions 15' of the slots as shown in Figures 8, 14 and 16. It is thus seen that the record in alignment with the slots will be maintained against movement through said slots by arms 88. Furthermore arms 88 hold the record in a sufficient 20 elevated position to enable the record to be moved upwardly by the chamfered portion 16' of the slots as the carriage is moved longitudinally relative to said record in either direction and into engagement with the upper surface of the platform 14 adjacent the opening 15 whereby the record will be maintained in its normal 25 position within the magazine 4.

It will now be understood that the record E aligned with the slots 16 and maintained against 30 downward movement by the arms 88 will pass downwardly through said slots onto the tracks 19 and 20 upon downward swinging movement of the arms. This swinging movement of the arms 88 is produced by a cam 90 secured to the cam shaft 29 adjacent one end thereof. Cam 35 90 is operatively connected with the shaft 89 by a cam follower arm 91 which is rotatably mounted upon a shaft 92, see Figure 6, positioned in a horizontal plane in front of the cam shaft 29 and which extends transversely through the cabinet A with the ends thereof secured in any suitable manner to the side walls *a* of said cabinet. This arm 91 extends rearwardly from the shaft 92 over the cam 90 into engagement 40 with the periphery thereof and is yieldingly maintained in contact with said cam by a spring 94 connected with the free end of the arm and with the partition *a*. The arm 91 is pivotally connected to one end of a link 95 which extends upwardly from said arm and has the upper end 45 thereof pivotally connected to a rock arm 96 secured to one end of the shaft 89. As the record carrier arms 88 are thus moved downwardly from the uppermost position as illustrated by full lines in Figure 6 to their lower or outermost position as illustrated by broken lines in said figure, the record aligned with the slots 16 will follow said arms downwardly and be guided by the guide tracks 19 and 20 to a position over the 50 turntable C into engagement with the horizontal portions 24' of the movable guide track 20 as shown by broken lines in Figure 6.

As the record approaches the horizontal position on the movable guide member 20 arms 88 move out of contact with the record and the forward edge of the record will engage a pair of record positioning fingers 98 arranged at the forward side of the turntable C. These guide fingers 98 are rotatably mounted on a horizontally disposed shaft 99 which is secured to a pair of brackets 100 mounted on the partition *a* at the forward side of the cam shaft 29 as illustrated in Figure 7. A similar pair of record positioning fingers 101 are positioned at the rear 70 side of the turntable C diametrically opposite

the positioning fingers 98. These rearwardly positioned fingers 101 are rotatably mounted on a shaft 102 secured to brackets 103 also mounted on the partition *a*. The fingers 101 are operatively connected with the fingers 98 by means of a rod 104 which is connected at its forward end to an extension 98' of one of the fingers 98 projecting below the shaft 99. The other end of the rod 104 is pivotally connected with one of the fingers 101 at a point above the shaft 102 so that the forwardly and rearwardly positioned fingers will simultaneously rock in a direction toward or from each other to bring them into and out of cooperative engagement with a record. 10

As shown in Figures 1 and 7, the means for 15 operating these fingers 98 and 101 comprises a cam 106 secured to the cam shaft 29. A cam follower pin or roller 107 adapted to engage the peripheral surface of the cam 106 is operatively connected with a rock arm 108 which has the 20 forward end thereof rotatably mounted upon the shaft 92. This arm 108 extends rearwardly from the shaft 92 to some distance beyond the cam 106 and has the inner or free end thereof connected to a spring 109 which is also connected with a 25 rod 110 extending transversely through the case A, said rod having the ends thereof connected with the side walls *a* of the case by any suitable means. The rock arm 108 is operatively connected with one of the rearwardly positioned 30 fingers 101 by a link 111 pivotally connected with said arm at one end and having the other end pivotally connected to a pendant portion 101' of one of said arms. The length of the rod 104 and the relation of the pivotal connections 35 thereof with the fingers 98 and 101 relative to the pivotal shafts 99 and 102 is such that when the fingers are in their outermost positions they will be spaced apart at their upper ends a distance greater than the diameter of the largest record 40 to be played.

The pivots 99 and 102 for the fingers 98 and 101 are positioned at equal distances either side of the turntable shaft *c* so that as said fingers are moved inwardly toward each other the record 45 engaged thereby will be brought into concentric relation with the turntable C. This movement of the fingers toward each other is produced by the spring 109 through the medium of the arm 108 and link 111 when the cam follower 107 is in registration with the recess 106' of the cam 106. 50 It will therefore be seen that irrespective of the size of the record said record will be brought into concentric relation with the turntable C as the arm 108 is released by the cam 106. As the cam continues to rotate the engagement of the wall of the recess 106' with cam follower 107 will rock the fingers 98 and 101 outwardly in directions away from the turntable and thereby release said record and permit the same to move into engagement with the turntable C. This movement of the record downwardly onto the turntable C is permitted by the action of the cams 28 upon the movable track 20 which permits the forward portion of said track to move downwardly simultaneously with the engagement of the fingers 98 55 and 101 with the record.

The records E are removed from the turntable C by means of a pair of record lifting or reversing arms 114 positioned one at either side of the 70 turntable C as illustrated in Figures 8 and 9. These arms 114 normally extend from a position in front of the turntable to a position at the rear thereof and are mounted to swing intermediate the arms 24 of the movable track 20. 75

- The rear end portions 114' of the arms 114 extend upwardly at substantially right-angles to the remaining portions thereof and are secured to a shaft 115 which is disposed in a horizontal plane at the rear of the turntable C intermediate said turntable and the lower ends of the arms 23 of the stationary track 19. The shaft 115 is rotatably supported in the upper ends of a pair of brackets 116 secured to the partition a'.
 5 10 It will now be understood that as the arms 114 swing upwardly a record contained on the turntable C will first be lifted from said turntable and as the arms proceed in their upward movement the rear edge of the record will engage the portions 114' of the arms so that the record will be lifted thereby to a plane above the turntable with the lower edge of the record positioned above the path of movement of the outer or free ends of the record carrying arms 88. The arms 114
 15 20 are swung to a position slightly beyond the vertical so that the upper end portion of the record carrier thereby will swing by gravity rearwardly relative to the turntable into engagement with the stationary guide track 19 as the arms 114 approach the extreme upper position of their movement as illustrated by broken lines in Figure 8. It will thus be seen that the record in moving from the turntable C to the inclined position in engagement with the stationary guide track 19
 25 30 will be positioned with the opposite side thereof facing forwardly from that when the record was moved downwardly from the magazine.
 It therefore follows that when the record is again moved onto the turntable the opposite or reverse side thereof will be facing upwardly in position to be played. The means for operating the record reversing arms 114 comprises a cam 118 secured to the cam shaft 29 as shown in Figures 1 and 8. This cam 118 engages a cam follower 119 in the form of a pin or roller which is operatively connected with a rock arm 120. This rock arm has the forward end thereof rotatably mounted upon the shaft 92 and extends rearwardly from said shaft to a considerable distance at the rear of the shaft 29. The cam follower 119 is yieldingly maintained in engagement with the peripheral surface of the cam 118 by spring 121 which has one end connected with the free end of the arms 120 and the other end thereof secured to the rod 110. The arm 120 is operatively connected with the arms 114 by a link 122 pivotally connected with the arm 120 intermediate the spring 121 and the cam follower 119. The other end of the link 122 is pivotally connected with a crank arm 123 secured to or made integral with one of the record reversing arms 114 to project rearwardly from the shaft 115.
 Associated with the carriage 12 is a manually operated control means which is adapted to coact with the means for operating the record carrier arms 88 and the record reversing arms 114 whereby any one or number of the records contained in the magazine 4 may be played either on one side or on both sides. This control mechanism, as illustrated in Figures 4, 5 and 15, comprises a plurality of, in this instance, 12 contact control arms 125, one for each magazine compartment 8'. These contact control arms are composed of brass or the like and are rotatably mounted upon a shaft 126 as shown in Figures 4 and 5 in electrical contact therewith. This shaft 126 is secured at its ends in supporting plates 127 which are secured to the lower side of one of the side rails 9 by brackets 128. The supporting plates 127 and shaft 126 are electrically

insulated from the brackets 128 and rail 9 by a spacing strip or member 129 composed of rubber fiber or other insulating material as shown in Figures 4 and 5. The contact control arms 125 are maintained in spaced relation to each other by spacing sleeves 130 mounted upon the shaft 126 intermediate adjacent arms and spring members 131 mounted between the outermost arms and the adjacent supporting plates 127.
 5 10

It will now be understood that the co-action of the spring 131 and spacing sleeves 130 will frictionally maintain the contact arms 125 in predetermined rotary positions relative to the shaft 126. The sleeves 130 are constructed to maintain the adjacent arms 125 spaced from each other a distance equal to the distance adjacent compartments 8' of the magazine 4 are spaced from each other. Mounted upon the carriage 12 is a spring contact member 133 which is secured to said carriage in insulated spaced relation therewith and in predetermined relation with the slots 16 by any suitable means. This spring contact member 133 as illustrated in Figure 4 extends downwardly beneath the carriage into the horizontal plane of the shaft 126 and has the lower end thereof formed arcuate as at 133' for contacting with the inner end of each of the arms 125 when the slots 16 are in registration with a corresponding record chamber 8'. The arms 125 are constructed in such a manner that when moved to a position inclined to the horizontal as illustrated by broken lines in Figure 4 they will be out of the path of movement of the contact member 133. The contact member 133 extends upwardly along one side of the carriage 12 and has the upper end thereof connected to a contact plate 135 which extends longitudinally of the carriage along the upper face thereof a distance equal to or greater than the longitudinal movement of the carriage and which is secured to said carriage 40 in insulated spaced relation therewith.
 15 20 25 30 35 40

Mounted upon the side rail 9 which carries the contact arm 125 is a yielding contact member 136 which is secured to said rail in insulated spaced relation therewith and extends inwardly therefrom over the adjacent edge of the carriage 12 into sliding contact with the plate 135 for electrically maintaining said plate and the spring contact member 133 in electrical connection with a source of potential during the reciprocating movement of the carriage.
 45 50

The operation of the apparatus will now be readily understood by referring to Figure 17 of the drawings in connection with the remaining figures thereof. Electrical energy is obtained from conductors 140 and 141 connected with any suitable source of potential. The positive conductor as 140 is provided with a manually operated control switch 142 and when said switch is closed current is supplied by wire 143 to the motor B which is maintained in operation for driving the shafts b and clutch member 78. At the beginning of the operation of playing one or more of a series of records contained in the magazine 4, the clutch 78 will be in engagement with the clutch element 76 and the tone arm D will be in the inoperative position at one side of the turntable C as illustrated in Figure 8, so that when the switch 142 is closed the cam shaft 29 will be operated by the motor B. Prior to the closing of switch 142 the carriage which will then be released by the detent 33 as shown in Figure 10, may be first operated by hand by means of the handle 85 to bring the slots 16 into predetermined relation with the first record desired to be played.
 65 70 75 80 85 90 95 100

In this instance the carriage is so positioned that the slots 16 are positioned one space in advance of the record to be played.

It will now be apparent that during the initial operation of the motor B and shaft b the cam 53 operated by the cam shaft 29 will actuate the cam follower 44 to first bring the detent 33 into engagement with the rack 32 and then move the carriage one tooth space rearwardly in the manner hereinbefore described and thereby bring the slots 16 into cooperative alignment with the selected record. As the carriage is thus moved into cooperative relation with the selected record the cam 90 will have been moved from the position shown in Figure 6 in the direction indicated by the arrow Y to bring the forward portion thereof into contact with the cam follower arm 91. As the cam 90 continues to rotate it will rock the arm 91 from the position shown by full lines in Figure 6 to the position indicated by broken lines in said figure. During this movement of the arm 91 the record carrying arms 88 will be moved downwardly about the axis of the shaft 89, thereby permitting the record in alignment with the slots 16 and which rests upon the arms 88, to move downwardly. The record is guided in its downward movement by the co-action of the arms 88 and guide tracks 19 and 20 to nearly a horizontal position, as indicated by broken lines in Figure 6, over the turntable C and into engagement with the forwardly located record positioning fingers 98.

During the initial rotation of the cam shaft 29 it will be understood that the movable guide track 20 will be maintained in its normal uppermost position by the cams 28. Prior to the engagement of the record with the fingers 98 the record operating arms 88 will have moved forwardly out of engagement with the record, due to a slowing up in the movement of the record as it assumes the horizontal position. As the record moves into engagement with the fingers 98 it will pass beyond the lower end of the stationary guide track 19 so that it will then be entirely supported by said fingers and the movable guide track 20. The fingers 98 are so related to the turntable C when in their outermost inoperative positions that the record engaging said fingers will be maintained thereby with the center thereof positioned in advance of the center of the turntable C.

As the record E engages the fingers 98 the movable guide track 20 is permitted to commence the downward swinging movement thereof by the cams 28. At about the time the track 20 begins the downward movement or shortly thereafter the arm 108 is released by the registration of the cam recess 106 in the cam 106 with the cam follower 107. As the arm 108 is thus released the spring 109 actuates said arm to produce movement of the fingers 98 and 101 toward each other and will bring them into engagement with the adjacent peripheral edge of the record irrespective of whether a ten inch record or a twelve inch record is being positioned upon the turntable.

It will be observed that during the movement of the fingers toward each other, the record will be brought into concentric relation with the turntable C due to the fingers 98 and 101 being moved toward each other with a uniform movement and also to the fact that the fingers of each pair engage the record at equal distances either side of the vertical plane passing through the center of the turntable longitudinally of the tracks 19 and 20. At about the time the fingers have thus brought the record into concentric re-

lation with the turntable C the movable track 20 will be in substantially the plane of the upper face of the table during its downward movement. The fingers 98 and 101 are then moved outwardly to release the record by the engagement of the cam 106 with the cam follower 107 thereby placing the record upon the turntable in concentric relation therewith and with the usual centering pin as c' of the turntable engaging in the center hole of the record. After the record has been thus placed upon the turntable C the movable track 20 is permitted to swing to a position below the turntable as illustrated by full lines in Figure 7. During this movement of the record positioning members, the cam shaft 29 will have been rotated 180° at which time a switch control pin or member 12' connected with the gear 12 mounted on the cam shaft will engage a contact member 144 of a normally open switch 145 and close said switch. This switch is connected by a wire 146 with the electro-magnet 82 and positive conductor 140.

It will thus be seen that as soon as the switch 145 is closed a circuit is completed through the electro-magnet 82, switch 145, wire 147, wire 148 and thence through the normally closed switch 69, wire 149 and a second normally closed switch 150 and wire 151 to the negative conductor 141. The electro-magnet 82 is thereby energized which effects the movement of the clutch member 78 out of engagement with the clutch element 76, whereby the cam shaft 29 is disconnected from the drive shaft b, into engagement with the clutch element 71, whereby the turntable is operatively connected with said shaft b. As the turntable C is now driven by the motor B the tone arm D may be moved from the inoperative position at one side of the turntable and the record thereon to the operative position with the needle carried thereby in engagement with the record on the turntable by any suitable means. The movement of the tone arm D into operative engagement with the record effects the opening of switch 150 due to a control element or lug 153 connected with the tone arm being moved out of 45 cooperative engagement with one of the contact arms as 150' of the switch 150 thereby opening the circuit associated with the electro-magnet 82 and causing said electro-magnet to be de-energized.

The record on the turntable is now played in the usual manner after which the tone arm D may be returned to its initial inoperative position manually or by a suitable power operating means not shown. During the movement of the tone arm D to the inoperative position thereof and before said tone arm reaches said inoperative position, a normally open switch 154 is momentarily closed by the engagement of a switch operating member 156, also connected with the tone arm D, 60 with one of the contact members as 154' of said switch. It will be understood that the member 156, as shown in Figure 17, will move outwardly beyond contact member 154' as the tone arm D moves toward the center of the record on turntable C during the playing of the record so as to be in position to actuate the contact member 154' as the tone arm returns to the inoperative position to close switch 154. As soon as the switch 154 is closed current will pass from the positive 70 conductor 140 through the electro-magnet 83 and wire 155 to the switch 154 and thence through wire 151 to the negative conductor 141. The electro-magnet 83 thereby energized will effect movement of the clutch member 78 out of en- 75

gagement with the clutch element 71 and into engagement with the clutch element 76 thereby disconnecting the turntable C from the drive shaft b and connecting the cam shaft 29 with said drive shaft. This closing of the switch 154 as hereinbefore stated, is prior to the time the tone arm D reaches its inoperative position and the switch 150 is closed by control element 153 so that the operating member 72' connected with the gear 72 will be moved out of engagement with the contact member 144 of the switch 145 permitting said latter switch to open and thus maintaining the electro-magnet 82 de-energized until the gear 72 is rotated three hundred sixty degrees. As soon as the cam shaft 29 is thus connected with the drive shaft b the record reversing arms 114 will be actuated by the engagement of the cam 118 with the cam follower 119 to produce upward swinging movement of said arms. During this swinging movement of the arms 114 the record will be lifted from the turntable and brought into engagement with the stationary guide track 19 as illustrated by broken lines in Figure 8. During this upward swinging movement of the arms 114 the arms 88 are moved rearwardly toward the record so that as the record engages the stationary track the record carrying arms 88 will engage the lower edge of said record, lift the record from the arms 114 and move the same upwardly through the slots 16 into the compartment 8' of the magazine 4 previously occupied by said record. As the record is thus returned to the magazine 4 the switch control member 72' will be in its initial position, switch 145 will remain open, the clutch 78 will remain in engagement with the clutch element 76 and the cam shaft 29 will continue to be operated by the drive shaft b.

It will now be observed that during this movement of the record operating mechanism to bring the record from the magazine onto the turntable and to return said record to the magazine, the cam shaft 29 will have rotated one complete revolution while the cam 53 will have rotated but one-half of a revolution. It therefore follows that as the record returns to the magazine the cam recess 53' of the cam 53 will be positioned diametrically opposite the cam follower 44 so that the detent 33 will remain in engagement with the rack 32 and maintain the carriage against movement relative to the magazine 4. The slots 16 are thus maintained in cooperative alignment with the record just returned to the magazine as the cam shaft 29 begins its second revolution. During this movement of the cam shaft 29 during its second revolution the record previously positioned on the turntable will again be returned to said turntable in the manner hereinbefore described by the downward swinging movement of the arms 88, the operation of the positioning fingers 98 and 101 and the downward swinging movement of the movable track 20.

As the record is thus brought into cooperative engagement with the turntable C the second time the cam shaft 29 will have completed 180° of its second revolution while the cam 53 will have been rotated another quarter of a revolution or a total of two hundred seventy degrees from the start. It will thus be seen that the cam follower 44 will remain in contact with the peripheral surface of the cam 53 while the switch operating pin 66 connected with cam 53 will have moved from the position illustrated in Figure 17, diametrically opposite the cam follower 44, three-fourths of a revolution into engagement with the

contact member 70 of the switch 69 to effect opening of said switch just prior to the engagement of the switch operating member 72' with the contact member 144. As the cam shaft 29 and gear 72 connected therewith complete the first half revolution of the second cycle of operation thereof, the switch 145 will be closed in the manner hereinbefore described. Inasmuch as the switch 69 is then in the open position the electro-magnet 82 will remain de-energized providing the circuit through said electro-magnet is not closed by the co-action of the contact arm 125 corresponding to the record compartment 8' from which the record on the turntable was received and the contact member 133 or by a manually operated switch 158 in the manner presently described.

When the electro-magnet 82 is thus maintained de-energized it will be obvious that the cam shaft 29 will continue to be operated by the drive shaft b so that instead of the record being permitted to remain on the turntable it is immediately lifted from the turntable by the action of the arms 114 and then returned to the compartment 8' previously occupied thereby in the magazine 4 by the record carrier arms 88. It will be observed that as the record is returned the second time to the magazine 4 said record will be again inverted by the action of the arms 114 so that said record will be arranged with the sides thereof in the initial position initially maintained thereby.

As the first record E is thus returned to the magazine the second time the cam shaft 29 will have completed two complete revolutions since the beginning of the operation of the machine while the cam 53 will have completed one revolution. The cam follower 44 will therefore be in registration with the cam recess 53' so that the detent 33 will be brought out of holding engagement with the rack 32 by the co-action of the springs 36 and 41 upon the detent 33 and bell-crank lever 39. When the rack 32 is thus released the carriage is free to be manually operated as desired to bring the slots 16 into predetermined relation with any of the records contained in the magazine 4 so that as the record operating mechanism is again actuated a second selected record will be brought into playing position upon the turntable C.

However, if it is desired to play the record next succeeding the record first played the machine is permitted to operate in the conventional manner. That is, carriage 12 is not manually moved so that as the cam 53 begins the second revolution thereof, cam follower 44 will be actuated thereby to first bring the detent 33 into engagement with the tooth of rack 32 next succeeding the one previously engaged thereby and then to move the carriage rearwardly one tooth space to bring the slots 16 into cooperative alignment with the next succeeding record in the magazine 4. As the slots 16 are thus brought into cooperative relation with the next succeeding record this record will be brought into playing position upon the turntable C in the manner hereinbefore described for the first record for playing. After this second record has been played it will then be automatically returned to the magazine with the sides thereof facing in the reverse order from that previously occupied thereby. After this second record has been returned to the magazine it is immediately moved from said magazine back onto the turntable after which the record may be immediately returned to the

magazine if it is not desired to play the same on the opposite side from that previously played or it may be caused to remain upon said turntable to be played as desired.

If it is desired to play the record on the second side this may be accomplished by the operator moving the contact arm 125 corresponding to the record selected to the horizontal position so that as the carriage is moved to bring the slot 16 thereof into cooperative alignment with the compartment 8' from which the record to be played was obtained, the circuit through wire 147 will be closed by the engagement of said contact arm with the contact member 133 mounted on the carriage 12.

When the switch 145 is closed by member 72' the circuit through the electro-magnet 82 will be completed although the switch 69 is maintained in the open position. This is due to the current passing from the conductor 140 through the magnet 82 and then from the wire 146 and switch 145 to the wire 147 after which the current passes through the wire 160, contact member 136, plate 135, contact member 133 to the contact arm 125 and thence through the shaft 126 to wire 161, to wire 149, switch 150 and wire 151 to the negative conductor 141. As the electro-magnet 82 is thus energized the clutch member 18 will be moved out of engagement with the clutch element 76 into engagement with the clutch element 77, thereby disconnecting the cam shaft 29 with the motor B and connecting the turntable shaft c with said motor for operating the turntable. As the turntable is thus being operated by the motor B the tone arm may again be brought into engagement with the record thereon for playing. After the record has been played said record may be automatically returned to the compartment of the magazine previously occupied thereby by the operation of the record lifting or reversing arm 114 and record carrying arms 188 in the manner hereinbefore described.

As the second record is thus brought into the magazine compartment the second time the carriage 12 will again be released by the detent 33 so that said carriage is free to be manually operated if it is desired to effect the playing of other than the next succeeding record. If the records in the magazine are to be played in succession the carriage 12 is only automatically moved rearwardly one magazine chamber space as each record is placed into the magazine the second time.

It will now be understood that during the operation of the machine or during the playing of a record, any one of the records in the magazine 4 may be rearranged as to the order thereof or replaced by another record. Furthermore, any previous setting of any one of the contact control arms or any number thereof may be changed whereby a record contained in the magazine or on the turntable or any number of records contained in the magazine may be caused to be played on one or on both sides as desired. When it is desired to play all of the records contained in the magazine on both sides the operator may set the machine by two methods to automatically accomplish this result. One, by moving all of the contact control arms 125 to the horizontal operative position so that they will be successively engaged by the contact member 133 as the carriage is brought into successive registration with the records in the magazine. Two, by closing the manually operated switch 75 158 contained in a wire 159 which is connected

at one end with the wire 147 and at the other end with the wire 161. When the switch 158 is thus closed the electro-magnet 82 will be energized each time the switch 145 is closed as the record is positioned upon the turntable C, irrespective of whether switch 69 is closed or open, so that the motor B will be disconnected from the cam shaft 29 and operatively connected with the turntable C for rotating said turntable.

When the switch 158 is thus closed and the switch 69 is opened by the member 66, current will pass from the positive conductor 140 through the electro-magnet 82, wire 146, switch 145, wire 147, to the wire 159 and thence through the switch 158 to the wire 161 and back to the negative conductor 141 through the wire 149, switch 150 and wire 151.

In addition to the above described mechanism and the operation thereof, I have provided a switch 68 which has one contact member as 67 20 thereof electrically connected with the positive conductor 140 at one side of the switch 142 by an extension 140' of said conductor. The other contact member as 67' of the switch 68 is connected by a wire 163 with the positive conductor 25 140 at the opposite side of the switch 142. This switch 68 as indicated in Figures 12 and 17 is mounted in such relation to the cam 53 that the switch operating member 66 connected with said cam will maintain the switch in the open 30 position only when the cam recess 53 is in registration with the cam follower 44. It will thus be seen that after the record changing apparatus is caused to operate by the closing of switch 142 the current for said operating mechanism will 35 continue to be supplied thereto although the manually controlled switch 142 is open until such time as the switch 68 is again opened by the member 66 which will not occur until the cam 40 53 has completed its cycle of movement. This 45 results in each record being returned to its allotted compartment in the magazine the second time before the machine ceases to operate, even though the switch 142 is opened at any time between the first removal of a record from the magazine and the replacement thereof in the magazine the second time.

It therefore follows that when the record changing apparatus is rendered inoperative both of the switches 68 and 142 will be in the open 50 position at which time all of the records will be in the magazine and they will be arranged with the sides thereof in the same order as when manually placed therein.

Although I have shown and particularly described the preferred embodiment of my invention, I do not wish to be limited to the exact construction shown, as various changes both in the form and relation of the parts thereof may readily be made without departing from the 55 spirit of the invention as set forth in the appended claims.

I claim:

1. In a phonograph record changing apparatus, the combination with a turntable, of a magazine for the records mounted in fixed relation relative to the turntable adjacent thereto, said magazine having a plurality of separate compartments, one for each record, a carriage, a record guide means mounted on said carriage, 65 means for operating the carriage to bring the guide means into cooperative alignment with a respective one of said compartments, means for controlling the movement of the record contained in said latter compartment along said 70 75

- guide means to bring the record from the magazine over the turntable in eccentric relation therewith, and separate means engageable with the record for bringing said record onto the turntable in concentric relation therewith.
2. In a phonograph record changing apparatus, the combination with a turntable, of a magazine for the records mounted in fixed relation relative to the turntable adjacent thereto, said magazine having a plurality of separate compartments, one for each record, a carriage, a record guide means mounted on said carriage, means for operating the carriage to bring the guide means into cooperative alignment with a respective one of said compartments, record operating means cooperating with the guide means for bringing the record in the compartment of the magazine in registration with the guide means onto the turntable and to return said record to said compartment including a carrier arm rotatably mounted to swing about an axis at one side of the guide means, positioning fingers engageable with opposite sides of the record, reversing arms rotatably mounted adjacent the turntable for lifting the record from said turntable and placing the same onto the guide means in the path of movement of the carrier arm, and means for successively operating said carrier arm, positioning fingers and reversing arms.
3. In a phonograph record changing apparatus, the combination with a horizontally disposed turntable, of fixed means for supporting a plurality of double faced disc records in substantially a vertical edgewise position at one side of the turntable, a record holding and selecting element movable relative to the supporting means normally contacting the records for releasably maintaining said records in said supporting means and for selecting a predetermined record therefrom, a record guide member connected with the holding and selecting means to move therewith and to extend therefrom toward the turntable adapted to slidably support a record thereon, record positioning means cooperating with the guide member and movable with respect to said guide member for shifting the selected record from the supporting means to the turntable and from the turntable back to the initial position of said record in the supporting means, said positioning means including a rock member actuated independently of the guide member from one side of the turntable to the opposite side thereof for turning said record during said shifting movement of the record to effect reversal of the positions of the record bearing surfaces of the record upon the placing of said record a second time upon the turntable whereby said record may be played on both sides.
4. In a phonograph record changing apparatus, the combination with a turntable, of a magazine for the records mounted in fixed relation relative to the turntable adjacent thereto, said magazine having a plurality of separate compartments, one for each record, a carriage, means supporting said carriage beneath the magazine, record guide means mounted on said carriage of such a character that the record may move by gravity therealong from the magazine to a position over the turntable, means for operating the carriage to bring the guide means into cooperative alignment with a respective one of said compartments, means including a holding member arranged at one side of the guide means associated with the carriage for releasing the record contained in the compartment aligned with the guide

means, and means for moving the released record along said guide means and for producing movement of the guide means with respect to the turntable while said carriage remains stationary to bring the record onto the turntable in concentric relation therewith.

5. In a phonograph record changing apparatus, the combination with a turntable, of a magazine for the records mounted in a plane above the turntable in fixed relation relative thereto, said magazine having a plurality of spaced substantially vertically disposed compartments, one for each record, each of said compartments having the lower side thereof open for the passage of a record to and from the compartment, a movable record retaining means mounted beneath the magazine adjacent to said lower open sides of the compartments for maintaining the records in said compartments, said retaining means being provided with a passageway therethrough for a record, means for actuating the record retaining means to bring said passageway into cooperative alignment with a predetermined one of said compartments to release the record therein, and means co-acting with the retaining means and including a substantially vertically disposed record guide member connected therewith in cooperative relation with the passageway for placing the released record over the turntable in cooperative relation therewith.

6. A record changing apparatus as set forth in claim 5 having additional means movable independently of the record retaining means and said guide member for lifting the record from the turntable and depositing the same onto the guide member into alignment with the passageway.

7. A phonograph record changing apparatus as in claim 5 having reversing arms rotatably mounted adjacent the turntable independently of the record retaining means for lifting the record from said turntable and placing the same onto the guide member in reverse order to the initial position of said record thereon in alignment with the passageway.

8. In a machine of the character described, a turntable, a frame adjacent thereto for supporting a group of records in predetermined spaced relation to each other, a movable record retaining means mounted adjacent the frame having a record guide means associated therewith, means for operating the record retaining means to bring said guide means into operative alignment with a predetermined one of the records contained in the frame, said guide means including a movable element extending from the record retaining means to a position adjacent the turntable for guiding the selected record to a position over said turntable, means for moving said movable element with respect to the turntable for depositing the record on said turntable, separate means operating independently of the guide means for moving the record from the turntable onto the said guide means, and additional means movable between the turntable and the record retaining means for moving the record along the guide means to return said record to the initial position thereof in the frame.

9. In a machine of the character described, a turntable, a group of records supported in predetermined spaced order above and at one side of the turntable, a record selector and guide means movable with respect to the group of records into position for receiving a predetermined record from said group and slidably supporting the same,

and means including an oscillatory carrier movable independently of the guide means between the group of records and turntable and cooperating with said guide means for placing said predetermined record on said turntable.

5 10. In a machine of the character described, a turntable, a group of records supported in predetermined spaced order above and at one side of the turntable, a record selector and guide means movable with respect to the group of records into position for receiving a predetermined record from said group and slidably guiding the same toward the turntable, means including an oscillatory carrier movable between the group of records and turntable and cooperating with the guide means during one stroke thereof for placing said predetermined record on said turntable, and an oscillatory reversing member movable between the turntable and guide means for moving the record from the turntable onto the guide means with the sides reversed and in position to be engaged by said carrier during the second stroke thereof to be returned by the cooperation of the carrier and guide means to its original position in said group of records.

25 11. In a machine of the character described, a turntable, a group of records supported in predetermined spaced order above and at one side of the turntable, a selector and guide means movable with respect to the group of records into position for receiving a predetermined record from said group and slidably guiding the same toward the turntable, a second guide means connected with the selector means to move therewith and to extend from in cooperative relation with the first mentioned guide means to a position over the turntable for guiding said predetermined record from said first mentioned guide means over the turntable, means including an oscillatory carrier movable between the group of records and turntable and cooperating with the second mentioned guide means for placing said predetermined record in a position over the turntable, and means for moving the second mentioned guide means to bring a portion thereof to a position below the turntable for depositing the records upon said turntable.

30 12. In a machine of the character described, a turntable, a group of records supported in predetermined spaced order above and at one side of the turntable, a selector and guide means movable with respect to the group of records into position for receiving a predetermined record from said group and slidably guiding the same toward the turntable, a second record guide means pivotally connected with the selector means to move therewith and to extend from in cooperative relation with the first mentioned guide means to a position over the turntable, means including an oscillatory carrier movable between the group of records and turntable and cooperating with the second mentioned guide means for placing said predetermined record in a position over the turntable, and means co-acting with the second guide means during the pivotal movement thereof for moving the record onto the turntable in concentric relation therewith.

35 13. In a phonograph record changing apparatus, the combination with a turntable, of fixed means mounted above the turntable for supporting a plurality of disc records in predetermined order adjacent thereto, a movable record selector and carrier mechanism mounted in cooperative relation with the turntable and record support means and including a vertically disposed record guide

element adapted to slidably support a record thereon and an oscillating carrier element coacting with said guide element during the sliding movement of a record along said latter element for shifting a selected record from the support onto the turntable, and means for moving said selector and carrier mechanism relative to the support to bring the guide element into cooperative engagement with a selected one of the records carried thereby.

40 14. In a phonograph record changing apparatus, the combination with a turntable, of a magazine for the records mounted in fixed relation relative to the turntable adjacent thereto, a movable record selector mechanism comprising a carriage mounted adjacent the magazine for movement with respect thereto and substantially normal to the axis of rotation of said turntable, guide means for slidably supporting a record secured to said carriage to extend therefrom over the turntable, means for moving the carriage relative to the magazine to bring said guide means into cooperative relation with the records carried by the magazine, and power operated means co-acting with said guide means for moving a record from the magazine to the turntable and for returning said record to the magazine.

45 15. A record changing apparatus as set forth in claim 14 wherein the power operating means includes a reversing member adapted to lift the record from the turntable and place the same on the guide means in reverse order to the position occupied during the movement thereof over said guide means from the magazine to the turntable so that the record may again be returned to said turntable by the cooperation of the guide means and the power operated means.

50 16. In a phonograph record changing apparatus, the combination with a turntable, a record magazine mounted adjacent the turntable, means for moving a record from the turntable to said magazine comprising a record guide member arranged in predetermined cooperative relation with the magazine for receiving a record therefrom, a reversing element adjacent the turntable adapted to swing about a fixed axis to bring a portion thereof from a position at one side of said turntable to a position at the opposite side thereof for lifting the record from the turntable onto the guide means, and separate means including an arm having an axis of movement fixed with respect to the magazine cooperating with said guide means for moving the record into the magazine.

55 17. In a phonograph record changing apparatus, the combination with a turntable and a magazine having a plurality of spaced record receiving compartments mounted adjacent the turntable in fixed relation thereto, of a record selector and carrier mechanism for moving the records from the magazine onto the turntable and from said turntable back to the magazine comprising a guide means in a position intermediate the magazine and turntable for slidably supporting the records therealong and movable relative to the magazine into successive registration with the compartments thereof, carrier arms rotatably mounted to swing about an axis arranged in fixed relation with the magazine adapted to govern the sliding movement of the record along the guide means, reversing arms rotatably mounted adjacent the turntable for lifting the record from said turntable onto the guide means into the path of movement of the carrier arms, and means for operating said carrier and reversing arms.

18. A device as set forth in claim 17 wherein the guide means includes a track having a portion thereof movable from a position in a plane above the turntable to a position below said turntable, and positioning fingers engageable with the edge of the record and cooperating with said track for bringing said record into concentric relation with the table.
19. In a phonograph record changing apparatus, the combination with a turntable and a fixed magazine for supporting a plurality of disc records in predetermined order adjacent said turntable, a record guide means movable relative to the magazine into successive cooperative relation with said records in the magazine for selec-

tively receiving the records therefrom, said guide means including a track member adapted to slidably support the records and mounted to swing about an axis arranged at one side of the turntable to bring at least a portion thereof from a position slightly above the turntable to a position below said turntable, means cooperating with the guide means for bringing a record from the magazine into a position over the turntable in eccentric relation therewith, and separate means cooperating with the track member during the movement thereof and movable with respect thereto for bringing the records onto the turntable in concentric relation therewith.

PAUL F. WILBER. 15
